UNITED STATES PATENT OFFICE.

CONRAD C. C. BURKHARDT, OF PHILADELPHIA, PENNSYLVANIA.

CROSSTIE FOR ELECTRIC LOCOMOTIVES.

Application filed October 1, 1927. Serial No. 223,343.

The object of my invention is to make an integral cast metal cross-tie which will have means for supporting the several parts of an electric locomotive or the like, and which will properly stiffen the structural frame of the locomotive, in addition to providing means for securing the brake-cylinders in position.

In the accompanying drawings:

Fig. 1 is a side view of my improved cross-tie;

Fig. 2 is a plan view;

Fig. 3 is an end view;

Fig. 4 is a transverse sectional view of the cross-tie on the line 4—4, Fig. 2; and

Fig. 5 is a sectional view on the line 5—5, Fig. 2.

The cross-tie 1 is made in the form of an integral casting and is of sufficient depth to form a rigid connection between the two side members of the locomotive frame which are shown by dotted lines 2, Fig. 2.

3 is a centre bearing plate, and projecting from each side of the structure are brake-fulcrums 4 which are made integral with the body of the cross-tie, the hangers also acting as brake-lever guides and made as clearly shown in the drawings.

5 are the brake-lever fulcrum brackets, to which is pivoted one end of the "dead" lever. 6 are the motor suspension lugs which are provided to support one end of the electric motor, the opposite end being hung on the axles.

At each end of the cross-tie are side bearing plates 7 which support the sides of the upper structure when the locomotive is traversing a curved track. The cross-tie has side plates 8 and a longitudinal central plate 10 having openings 11. 12 are the end plates which abut against the frame 2 of the locomotive, and 14 and 13 are respectively the top and bottom plates. 15 are transverse reinforcing plates which extend from one side plate to the other.

The structure is provided with suitable openings so that access may be had to all parts of the casting. Furthermore, this construction makes a comparatively light casting with the required strength.

The cross-tie is recessed at 9 on each side of the centre bearing and close to the point

where it is attached to the side frames, and in each recess of the cross-tie is a longitudinally arranged brake-cylinder 16 shown by dotted lines, Fig. 4.

The brake-cylinder has lugs 17 which are shown by dotted lines and which are attached to pads 18 on the integral casting. At each side of the recess are flanges 19 which are also recessed at 20 for the extension of the brake-cylinder structure. It will be readily noted that the brake-cylinder structure does not rest on the recessed portions but are rigidly supported on the pads 18.

By the above invention I am enabled to make a cross-tie in one piece having the brackets and other supports with different parts of an electric locomotive, so that the brake-cylinders can be properly supported on the frame in a horizontal position.

It will be understood that in some instances the cross-tie may be made without the motor-suspension lugs, and that the cross-tie can be used on any type of passenger or freight equipment.

I claim:

1. A cross-tie made in a single casting and having a centre bearing, said casting being arranged to fit between the frames of a locomotive, and having a recess at each end for a brake cylinder.

2. A cross-tie made in a single casting and having a centre bearing plate, side bearings arranged to fit between the frames of a locomotive, and recessed at each end for the reception of a brake-cylinder, the cross-tie being so designed that the brake-cylinders can be rigidly secured to said cross-tie.

3. A cross-tie made in a single casting and having a centre bearing and side bearings arranged to fit between the frames of the locomotive, and having a recess at each end for the brake-cylinders, and having pads to which the brake-cylinder structures are secured.

4. A cast metal cross-tie made in a unitary structure having a centre bearing, side bearings, and recessed at each end for the reception of brake-cylinders, and having integral brake-hangers, fulcrums, and motor-supporting brackets.

CONRAD C. C. BURKHARDT.
